(57) **CLAIM**

The ornamental design for a monitor frame, as shown and described.

DESCRIPTION

FIG. 1 is a perspective view of a first embodiment of a monitor frame showing our new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 1; FIG. 11 is an enlarged view of portion 11 shown in FIG. 1; FIG. 12 is an enlarged view of portion 12 shown in FIG. 2; FIG. 13 is an enlarged view of portion 13 shown in FIG. 2; FIG. 14 is an enlarged view of portion 14 shown in FIG. 2; FIG. 15 is an enlarged view of portion 15 shown in FIG. 2; FIG. 16 is a perspective view of a second embodiment of the monitor frame;

FIG. 17 is another perspective view thereof;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof;

FIG. 23 is a bottom plan view thereof;

FIG. 24 is an enlarged view of portion 24 shown in FIG. 16;

(Continued)

FIG. 25 is an enlarged view of portion 25 shown in FIG. 16;
 FIG. 26 is an enlarged view of portion 26 shown in FIG. 16;
 FIG. 27 is an enlarged view of portion 27 shown in FIG. 17;
 FIG. 28 is an enlarged view of portion 28 shown in FIG. 17;
 FIG. 29 is an enlarged view of portion 29 shown in FIG. 17;
 and,
 FIG. 30 is an enlarged view of portion 30 shown in FIG. 17.
 The dash-dash broken lines in the drawings depict portions
 of the monitor frame that form no part of the claimed design.
 The dot-dash broken lines represent boundaries of the
 enlarged portions and form no part of the claimed design.

1 Claim, 30 Drawing Sheets
